SPEED-ETCHING MACHINE

Werner Moll, Parallelstr. 6, Solingen-Wald, Germany
Filed May 10, 1960, Ser. No. 28,151
Claims priority, application Germany June 13, 1959
5 Claims. (Cl. 134—191)

The present invention relates to a speed-etching machine.

Recently, new etching methods have been known which operate without gradual etching. These methods provide automatically for the protection of the etching sides during the etching operation. Etching emulsions are used in this instance. Aside from the faster working process, the so-called under-etching is avoided.

Such etching methods are performed on etching machines which receive the etching plate in a horizontal position and which make possible a spraying of this etching plate which, preferably, is subjected to an additional movement.

The spraying of the etching plate is brought about by, among other means, throwing up the etching emulsion disposed below the etching plate. It has been proposed to use, for instance, flush wheels for throwing up said etching emulsion. Such flush wheels are, however, not favorable for the reason of servicing the same and for the reason of difficulties in manufacturing the same.

It has also been proposed already to feed the etching liquid under pressure into tubes. The tubes have sprayings disposed opposite the etching plate. They are located above the level of the etching emulsion, so that the etching spray may approach freely the etching plate. The remainder of the etching emulsion dripping from the etching plate falls back into the receiving van or receptacle of the machine. This spraying with a spray leads to unequal etching depth. For this reason it has also been proposed already to break substantially this spray and to obtain a greater evenness in the depth of the etching effect by movement of the spraying perforations.

Finally, it is also known to stir up the etching liquid immediately below its liquid level by means of a rake-like hoop and thus wet the etching plate. These devices require again mechanically moved parts. In order to avoid such mechanically moved parts, it has also been proposed before to stir up the surface of the etching liquid by means of tubes disposed below the level of the etching liquid and fed with pressurized air. This method, however, requires the additional use of pressurized air and still does not provide an extensively equal wetting of the etching faces, aside from the fact, that the application of pressurized air leads to a faster exhaust of the etching liquid.

It is, therefore, one object of the present invention to provide a speed-etching machine which brings about a wetting of the etching plate without any mechanically moved parts by an equal striking over the etching plate with sufficiently intensive wave crests produced in the etching liquid.

It is another object of the present invention to provide a speed-etching machine which comprises tube sections disposed parallel to each other as well as parallel to two oppositely disposed walls of a receptacle and arranged with its perforations permitting a bundled liquid stream below the level of the etching emulsion for feeding such etching emulsion thereto under pressure.

Due to this arrangement, the liquid stream, emerging under pressure from the perforations, creates wave crests on the surface of the etching emulsion disposed in the receptacle, which crests perform a reciprocating movement in accordance with a predetermined rhythm and thereby move along the undersurface of the etching plate. The

2

pendulum movement of the wave crests is produced by the liquid flow falling into the receiving receptacle upon return from the etching plate. These liquid quantities start the wave movement of the etching emulsion in the

receptacle. This wave movement on the other hand leads away from the etching emulsion spray emerging from the tubes. Upon the first start of the machine, the etching emulsion stream moves perpendicularly from each perforation. It creates a liquid crest directly towards the etching plate. The emulsion dripping from the etching plate creates, however, in the remaining etching emulsion, standing in the receiving receptacle, a wave movement. By means of the latter, the etching emulsion stream emerging from each of the perforations is diverted within the rhythm of this wave movement. The wave movement is retained due to the continuous reflections on the side walls of the receptacle. Due to the parallel arrangement of the walls to the rows of perforations of the tube sections, a fast and linear reciprocating wave crest is formed above each of the rows of perforations. This leads to an absolutely equalized etching performance.

It is another object of the present invention to provide a speed-etching machine, wherein the tube sections are formed by a serpentine tube, the two ends of which are connected with the pressure side of a pump, leading to a particularly favorable embodiment of the present invention and bringing about an equalization of the etching process.

The feeding of the etching emulsion from two ends of a closed serpentine tube has the effect that substantially at all places of the serpentine tube equal pressure prevails. The pressure losses are to a great extent compensated and equally distributed over the entire length of the tube sections, respectively. Substantially the same quantity of liquid emerges at about the same pressure from each of the perforations.

It is yet another object of the present invention to provide a speed-etching machine, wherein a favorable and stable embodiment is given, particularly as to mounting the device, by mounting the serpentine on a grate in the receptacle by means of stop blocks entering the curved portions of the serpentine.

These retaining means, particularly having no highly projecting securing means disposed within the range of the tube sections, assure a reliable working process.

It is also a further object of the present invention to provide a speed-etching machine, wherein the easily cleaning possibility of the serpentine is brought about by an arrangement according to which the tube sections are crosswise divided in relation to their parallel arrangement and enter into crossbores of a batten rigidly secured in the receptacle with their open ends formed by the crosswise division, said batten having a properly fitting seat at said cross-bores. Due to this formation, it is possible to remove certain tube sections from the speed-etching machine by removing the open ends from the cross-bores of the batten, if necessary, upon prior loosening of a screw retaining the particular tube section. It is even not necessary to empty the receptacle containing the etching emulsion for such removal. Furthermore, such formation permits the replacement of individual tube sections. In addition, an appreciable advantage is also given by such arrangement as to the manufacturing technique, and particularly since only individual tube sections may be manufactured independently from each other.

An advantageous embodiment is given in this direction, in accordance with the present invention, by the fact that the tube sections are formed as a serpentine tube which is divided along the median length and the ends being inserted from opposite sides into corresponding cross-bores which project completely through the batten.

With these and other objects in view, which will become apparent in the following detailed description, the present invention will be clearly understood in connection with the accompanying drawings, in which:

FIGURE 1 is a front elevation of the etching machine, partly in section;

FIG. 2 is a side elevation of the etching machine;

FIG. 3 is a side elevation similar to that shown in FIG. 2, however, with lifted cover of the etching machine;

FIG. 4 is a rear elevation of the etching machine;

FIG. 5 is a section along the lines 5—5 of FIG. 1;

FIG. 6 is a section along the lines 6—6 of FIG. 1;

FIG. 7 is a section along the lines 7—7 of FIG. 1;

FIG. 8 is a section through the receiving receptacle of the etching machine at an enlarged scale, showing schematically the condition of the etching emulsion at one point;

FIG. 9 is a section similar to that shown in FIG. 8, yet at a later moment of the movement of the etching emulsion than that shown in FIG. 8;

FIG. 10 is a front elevation of another embodiment of the etching machine, partly in section; and

FIG. 11 is a section along the lines 11—11 of FIG. 10.

Referring now to the drawings, and in particular to FIGS. 1 to 4, the etching machine comprises a lower frame 1 wherein the motor 2, coupled with the centrifugal pump 3, is mounted. The control of the motor 2 is obtained from a switching device 4. The motor 2 operates in accordance with a program control and is non-gradually controllable, in order to adjust the output of the centrifugal pump 3. The entrance opening of the centrifugal pump 3 is connected with a receiving receptacle 5 of the etching machine by means of the feeding conduit 6. Preferably, two entrances 6' and 6'' are provided in the receiving receptacle 5. A heating coil 7 and a cooling coil 8 are disposed at the bottom of the receiving receptacle 5. Both are controlled by a common thermostat, in order to maintain the temperature of the etching emulsion 9 at a constant level. The thermostat is connected for this purpose with the temperature feeler 10, which projects into the etching liquid 9.

A grate 11 is disposed above the serpentines 7 and 8. The serpentine tube 12 rests on the grate 11. The serpentine tube 12 forms the tube sections 12' disposed parallel towards each other and interconnected individually by the curve sections 12''. The stop blocks 13 sit rigidly in the curved portions 12'' of the tube sections. The stop blocks 13 (FIG. 5) are secured to the grate 11 by means of screws 13'. By such arrangement, the serpentine tube 12 is immovably secured. The two ends 14 and 14' of the serpentine tube 12 are connected with the pressure side 15 of the centrifugal pump 3. This connection is brought about by a forked member 16 which in turn is in connection with the pressure side 15 of the centrifugal pump 3. The cross-section of the tube of the forked portion 16 is larger than the cross-section of the tube of the serpentine tube 12, so that a pressure increase is achieved due to the reduction in the cross-sections at the points 16'.

The receiving receptacle 5 may be closed by means of the cover plate 17. The cover plate 17 is hinged at its rear end to the receiving receptacle 5. A lever linkage 18, having a counter-weight 19, permits the opening of this cover plate 17 by raising the same. At the underside of the cover plate 17 is disposed the receiving plate 20 for the etching plate 21. The receiving plate 20 is coupled with a planet drive 22. Due to this arrangement, the receiving plate 20 performs a rotary movement upon its median axis 20', whereby this median axis 20' performs an additional circular movement.

The tube sections 12' are disposed perpendicularly to the back wall 5' of the receiving receptacle 5 and parallel to the side walls 5'' of the receiving receptacle 5. They are equipped with perforations 23 directed towards the cover plate 17.

Referring now to the embodiment disclosed in FIGS.

10 and 11 which follows substantially the embodiment described above, the grate 11 carries the batten 26. The individual, straight tube sections 12' which are disposed parallel to each other, are divided along their center. The ends 27 formed by the cross division enter into fitting seats provided in cross-bores 28 of the batten 26 disposed on the grate 11, and in particular on oppositely disposed points, so that a co-axial arrangement is achieved.

The width of the batten 26 is narrower than the distance between two adjacent perforations 23, so that the continuous arrangement of the perforations 23 and the completely equalized working operation of the machine is not interfered with by the arrangement of the batten 26.

The present invention operates in the following manner:

The receptacle 5 is filled with the etching emulsion to a level that the tube sections 12' are disposed below the level 9' of the etching emulsion. In view of the arrangement of the serpentine on the grate 11 disposed close to the bottom of the receiving receptacle, this condition is always present upon normal filling of the receiving receptacle 5.

Upon starting the motor 2, the pump 3 feeds etching emulsion 9 from both ends 14 and 14' to the serpentine tube 12 under pressure by means of the feeding pipe 6. The streams 24 of the etching emulsion emerge then from the perforations 23. The streams 24 of the etching emulsion are at first directed perpendicularly in upward direction for a short time due to such arrangement. They produce the wave crests 25 in the etching emulsion 9, which wave crests 25 hit the etching plate 21. Thus, no point-shaped stream is directed towards the etching plate 21.

The etching emulsion 9 reflected and dripping off the etching plate 21 causes a wave movement to the entire etching emulsion 9. The wave movement brings about a diversion of the stream 24 of the etching emulsion. Such diverting position is shown schematically in FIG. 8. The motion of the bath 9 of the etching emulsion changes the direction of the stream 24 of the etching emulsion from the direction indicated in FIG. 8, so that the stream swings into the position shown schematically in FIG. 9. Due to the series arrangement of the individual perforations 23, each series being disposed parallel to the next series, a pendulum movement of wave crests 25 of the etching emulsion 9 is created. The pendulum movement takes place regularly in the direction of the double arrow x in FIG. 8. Due to the parallel position of each of the series of perforations 23 to the two oppositely disposed side walls 5'' of the receiving receptacle 5, an extremely equalized movement is obtained within a short time, which movement is not disturbed by different reflections on the side walls 5''.

The wave crests 25 of the etching emulsion 9 strike over the etching plate 21 equally and in rhythmic steps. An absolutely equally deep etching effect is achieved in connection with the additional rotation of the etching plate 21. The fact that no stream bundle is directed towards the etching plate 21, and since besides that a continuously changing hitting angle will be encountered, assures that the emulsion film formed for the protection of the sides of the etching plate is not disturbed.

If one or a plurality of perforations 23 is clogged up, or if dirt has accumulated inside of the serpentine tubes 12, the particular tube portion may be removed in accordance with the embodiment disclosed in FIGS. 10 and 11 upon loosening of the screw 13' by pulling out axially the end 27 of the particular tube portion from the cross-bores 28 of the batten 26. The embodiment disclosed in FIGS. 10 and 11 is, therefore, particularly suitable for larger machines wherein the complete removal of the correspondingly long serpentine tube would cause appreciable difficulties.

While I have disclosed several embodiments of the present invention, it is to be understood that these embodiments are given by example only and not in a limit-

ing sense, the scope of the present invention being determined by the objects and the claims.

I claim:

1. A speed-etching machine comprising means for receiving a plate in horizontal position, a receptacle adapted to receive an etchant and having at least two parallel, oppositely disposed walls and receiving removably said plate receiving means above and close to the etchant level in said receptacle, a plurality of tubes disposed below said plate receiving means, and means for securing said tubes to said receptacle, said tubes having straight sections disposed parallel to each other and to said walls of said receptacle and curved sections connecting each pair of adjacent tubes, and said straight sections of said tubes having a plurality of spraying perforations, means for feeding said etchant from said receptacle into said tube sections under pressure, and said spraying perforations of said tube sections being disposed below the level of said etchant.

2. The speed-etching machine, as set forth in claim 1, 20 wherein said pressure feeding means for said etchant comprises a pump, said tubes consist of a serpentine tube having two ends, and means connecting each of said ends with said pump.

3. The speed-etching machine, as set forth in claim 2, wherein said tube securing means comprises a grate, disposed inside of said receptacle, and a stop block disposed in each curved portion of said serpentine tube and secured to said grate, thereby retaining said serpentine tube in a predetermined position relative to said grate.

5 4. The speed-etching machine, as set forth in claim 1, wherein said tube securing means comprises a batten disposed inside of and secured to said receptacle, and said tubes are divided across said sections along the axis of said batten and form open ends entering into crosswise disposed bores to form fitting seats of said batten.

10 5. The speed-etching machine, as set forth in claim 4, 15 wherein corresponding bores of said batten are arranged coaxially relative to each other.
